UNITED STATES PATENT OFFICE

ARCHIBALD ALLAN, OF TYNEMOUTH, AND JAMES MIRREY, OF EAST BOLDON, ENGLAND, ASSIGNORS TO A. REYROLLE & COMPANY LIMITED, OF HEBBURN-ON-TYNE, ENGLAND, A COMPANY OF GREAT BRITAIN

ELECTRIC SWITCH GEAR

Application filed April 28, 1928, Serial No. 273,759, and in Great Britain June 11, 1927.

This invention relates to electric switch-gear and particularly to that type of gear which is operated by air or other fluid under pressure.

5 In switchgear according to the present invention the switch-operating rod or plunger is operated directly by pneumatic or other fluid pressure applied directly to a cylinder or piston mounted on the rod.

10 Conveniently a cylinder is attached to the rod or plunger to form an extension thereof. This cylinder cooperates with a fixed head or piston and compressed air is admitted through a central tube into the cylinder 15 through a hole in the tube just above the fixed head to move the cylinder and the rod and close the switch.

This central air inlet tube carries the fixed piston or head at its lower end and thus may 20 be regarded as a stationary piston rod. It is fixed at its upper end by passing through a cap into a chamber at the upper end of a casing which encloses the movable cylinder. This chamber is in direct communication with 25 the compressed air supply.

The upward movement of the cylinder is arranged to cause rotation of a notched disc or cam cooperating with a catch or detent to hold the switch in its closed position until 30 released by an electromagnetic trip or like mechanism. When released the switch is opened or its opening movement accelerated by a kick-off spring which is conveniently arranged to act on the upper end of the cylinder.

35 Preferably the outside of the cylinder is formed as or provided with a rack engaging with a toothed pinion on a shaft which carries the notched disc or cam.

40 The cylinder with its rack is enclosed in a casing projecting above and below the tank cover and in the lower part of such casing is fixed a head or gland through which the plunger rod passes. Somewhat above this gland are shaped openings in the casing communicating with the oil in the tank and thus, on the opening movement of the switch, i. e. the downward movement of the plunger rod and cylinder, the oil passes freely out of the casing through the openings. Towards the 45 end of this movement the cylinder closes these

openings and the oil can no longer pass freely through them but has to find its way through the various clearance spaces. Thus a dash-pot or retarding effect is also provided at the end of the opening movement.

55 This improved construction of pneumatic operating gear is very suitable for use in multi-phase switchgear, and in one construction of three-phase gear the chambers at the top of the casings are all in connection with 60 a common pipe through which the supply of compressed air passes. This supply is controlled by an electromagnetically-operated valve preferably arranged so that when it cuts off the supply, that is when the switches 65 have been closed, it opens the supply pipe to the atmosphere.

70 The electrical circuit for operating the pneumatic admission valve is also controlled by a switch operated by the trip coil magnet so that the circuit is interrupted when the trip coil is energized.

75 By this means the air supply is cut off immediately the trip coil is energized, and such compressed air as has been admitted is allowed to escape so that the switch immediately opens.

80 This construction affords the protection that is provided by the "free handle" feature generally embodied in switch-operating mechanisms.

85 The shafts carrying the pinions which engage with the cylinder racks are coupled together preferably by couplings which allow for small differences in alignment, and one mechanism is provided for holding and tripping all three switches. This mechanism conveniently comprises a notched disc or cam controlled 90 through a toggle by a trip electromagnet.

95 This arrangement is extremely simple and provides for the simultaneous direct pneumatic operation of all three phase switches of the gear.

In the accompanying drawings,

Figure 1 is a central vertical section through a portion of one construction of switchgear according to this invention,

Figure 2 shows diagrammatically the es- 100

sential parts of a preferred pneumatic and electromagnetic control mechanism, and

Figure 3 is a diagrammatic perspective view of one embodiment of the invention as applied to three-phase switchgear.

In these drawings, A represents the plunger rod of a switch carrying a cross bar A¹ which, when the switch is closed, completes the circuit between two fixed brushes or other contacts B (Figure 2). Surrounding this plunger rod A is a casing C (Figure 1) secured to a hood D which may be part of the cover of a tank containing oil in which the switch operates.

At the top of the casing C is a fixed head or chamber E to which is secured a central tube E¹ having at its lower end a fixed head or piston E². With this fixed piston E² operates a cylinder F provided with a head F¹ sliding on the fixed tube or piston rod E¹. The lower end of this cylinder F is secured to the plunger rod A and a rack F² on one side of the cylinder engages with a toothed pinion G¹ mounted on a shaft G. In all the figures the switch is shown in its closed position, i. e. with the plunger rod A raised. This upward or closing motion is brought about by fluid under pressure, hereinafter referred to as compressed air, admitted from a pipe H into the chamber E whence it passes down through the tube E¹ and out at an opening E³ into the space between the head F¹ of the cylinder F and the fixed piston E².

It will be seen by reference to Figure 1 that there are two small tubes within the central tube E¹ each of these terminating in a capped outlet at the top. One of these small tubes J ends just above a space E⁴ in the fixed piston E² and it is provided to allow any moisture which may accumulate in that space to be blown off. The lower end of the other small tube J¹ passes through the piston E² and is intended to prevent back pressure between the lower face of the fixed piston E² and the lower closed end of the cylinder F as the latter rises. It also allows the cylinder to fall freely on the opening movement.

If desired any suitable form of valve may be provided to cooperate with this tube J¹ to close it just before the closing (upward) movement of the cylinder is completed and thus introduce a dashpot effect at the end of the closing stroke. Or alternatively, the lower end of the cylinder may be shaped to cooperate with a correspondingly formed projecting part of the piston with the same object. Neither of these devices is essential and they are not shown in the drawings.

The opening (downward) movement of the cylinder and plunger rod may be mainly due to gravity, but a kick-off spring K is provided to accelerate the initial portion of the opening movement. The lower end of the casing C is provided with a gland C¹ through which the plunger rod A passes, and at some

convenient level above that gland a shaped opening C² is formed in the casing. When, as is usually the case, the switch is oil-immersed, the oil in the casing is, on the downward movement of the cylinder, expelled through the opening C² into the surrounding tank. The area of the opening is gradually diminished by the descending lower end of the cylinder and the opening finally closed so that any remaining oil has to find its way out into the tank through various small clearance spaces. This introduces a dashpot effect at the end of the opening stroke.

The general operation will now be described with reference to the diagram forming Figure 2. The pipe H is connected to a port L which can be placed in communication either with a source of compressed air at L¹ when an inlet valve L² is opened (as shown) against the action of its spring L⁸, or with the atmosphere through the port L³ when the inlet valve L² is closed and an outlet valve L⁴ opened. These two valves are on a spindle L⁵ provided with a piston L⁶ in a cylinder containing the outlet port L³ and an inlet L⁷. This inlet L⁷ communicates with a port M in a relay air valve chamber M¹ provided with a spring-controlled air inlet valve M² and an outlet valve M³. These two valves M² and M³ are on a spindle M⁴ which can be raised against the action of a spring M⁵ by an electromagnet M⁶ in a circuit shown as controlled by a switch M⁷. There is a gap at N in the circuit of the electromagnet M⁶ closed by the armature of a trip electromagnet N¹ when that magnet is deenergized but opened when the trip circuit is closed.

On the shaft G carrying the pinion G¹ is mounted a notched or cam disc O. For the sake of clearness in the diagram forming Figure 2 this is shown separately, but the two shafts are each lettered G and the chain line connection indicates that they rotate together. A pivoted detent lever P has a roller P¹ which engages with the notch in the disc O, as shown in full lines in Figure 2, when the shaft G has been rotated by the raising of the cylinder F to close the switch. In this closed position the switch is retained by an arrangement of pivoted links P² which form a toggle controlled by a lever P³. In Figure 2 the toggle is shown in full lines in the set position and in chain lines in the position which it takes up when the toggle is broken by the lever P³ being operated by the trip electromagnet N¹ or by a hand trip N². It will be understood that as soon as the toggle is broken the detent lever P can rise under the action of the disc O which is rotated by the rotation of the shaft G due to the opening (downward) movement of the cylinder F and plunger rod A.

In Figure 2 it is assumed that the trip electromagnet N¹ is deenergized and that the circuit of the electromagnet M⁶ has just been

closed by the switch M^1 . This has opened the relay air valve inlet M^2 and allowed compressed air to pass from L^1 through the chamber M^1 and port M to the inlet port L^1 . The piston L^6 has moved to the left, thus opening the main inlet valve L^2 and admitting compressed air from L^1 through the port L to the pipe H . Consequently the switch has been closed, the detent lever P has fallen under the action of gravity or a spring (not shown) and has engaged the notch in the disc O and the toggle P^2 has assumed its set position.

If it be assumed that the closing of the switch M^1 controlling the relay air inlet valve is only for a short period of time, which is normally the case, then as soon as the switch is opened the spring M^5 will close the relay air inlet valve M^2 and open the outlet valve M^3 . L^7 is then placed in communication with the atmosphere through the port M and the valve spindle L^5 will move to the right under the action of its spring L^8 . This cuts off the compressed air supply L^1 from the port L and pipe H and by the opening of the valve L^4 places that port and pipe in communication with the atmosphere through the port L^3 . Thus, although the switch is closed and retained closed by the detent lever P and its toggle, it is ready to open instantly when the toggle is broken by the trip. It should be noted that the control of the circuit of the electromagnet M^6 by the trip electromagnet N^1 provides a very efficient "free handle" action, for even if the valve spindle M^4 is in the act of being raised by its electromagnet M^6 , and conditions arise which energize the trip electromagnet N^1 , the electromagnet M^6 is immediately deenergized and the movements of the air inlet valves necessary for the closing of the switch cannot be completed.

Figure 3 is intended to show the application of the invention to three-phase switchgear. The righthand switch is shown in elevation enclosed in its casings, the intermediate switch has its casings removed, the cylinder F being shown in elevation, and in the lefthand switch the cylinder is shown partly in section. It will be seen that there is one air supply pipe H for all three switches controlled by a valve L^9 which would be constructed so as to operate as described in detail with reference to Figure 2. The shaft G is in a number of lengths joined by couplings G^2 which allow for slight differences in alignment, and one notched disc O with its detent and trip mechanism suffices for all three switches.

What we claim as our invention and desire to secure by Letters Patent is:—

1. In electric switchgear the combination of a switch-operating rod, a cylinder forming an extension of such rod, an inlet tube within said cylinder, a head on said tube constituting a piston for the cylinder, an opening in said tube permanently connecting cylinder space above said head to said tube, a source of fluid under pressure and an electro-magnetically-operated valve controlling the flow of fluid from said source to said opening in said inlet tube to move said cylinder and switch-operating rod.
2. In electric switchgear the combination of a switch-operating rod, a cylinder forming an extension of such rod, an inlet tube within said cylinder, a head on said tube constituting a piston for the cylinder, an opening in said tube permanently connecting cylinder space above said head to said tube, a source of fluid under pressure, a supply pipe from said source to said inlet tube, an electromagnetically-operated valve controlling the flow of fluid from said source to said supply pipe, means in said valve for opening said supply pipe to the atmosphere.
3. In electric switchgear the combination of a switch-operating rod, a cylinder forming an extension of such rod, an inlet tube within said cylinder, a head on said tube constituting a piston for the cylinder, an opening in said tube permanently connecting cylinder space above said head to said tube, a source of fluid under pressure, a supply pipe from said source to said inlet tube, an electromagnetically-operated valve controlling the flow of fluid from said source to said supply pipe to move the cylinder and switch in one direction to close the switch, means in said valve for connecting said supply pipe to atmosphere, and means operative when said supply pipe is connected to atmosphere for moving said cylinder and switch-operating rod in the other direction to open the switch.
4. In electric switchgear the combination of a switch-operating rod, a cylinder forming an extension of such rod, an inlet tube within said cylinder, a head on said tube, a source of fluid under pressure, a supply pipe from said source to said inlet tube, a valve controlling the flow of fluid from said source to said supply pipe, means in said valve for opening said supply pipe to the atmosphere, an electromagnet controlling said valve, a circuit including said electromagnet and having a gap therein, a detent for holding said switch-operating rod when the switch is closed, trip mechanism for releasing said detent, an electromagnet for operating said trip mechanism, said electromagnet when deenergized closing the gap in the circuit containing the valve-operating electromagnet and opening said gap when energized.
5. In electric switchgear the combination of a switch-operating rod, a cylinder forming an extension of such rod, an inlet tube within said cylinder, a head on said tube, means for admitting fluid under pressure to said inlet tube to move said cylinder and switch-operating rod, a rack on said cylinder, a shaft bearing a pinion engaging with said rack, a detent engaging with said shaft to

125 130

retain said cylinder and switch-operating rod in the closed position of the switch, and trip mechanism for releasing said detent.

6. In electric switchgear the combination of a switch-operating rod, a cylinder forming an extension of such rod, an inlet tube within said cylinder, a head on said tube, means for admitting fluid under pressure to said inlet tube to move said cylinder and switch-operating rod, a rack on said cylinder, a shaft bearing a pinion engaging with said rack, a detent engaging with said shaft to retain said cylinder and switch-operating rod in the closed position of the switch, toggle mechanism for controlling said detent, trip mechanism for breaking said toggle, and an electromagnet for operating said trip mechanism.
